UNITED STATES PATENT OFFICE

2,081,396

SLIDE FASTENER

Didrick Dyresen, Billerica, Mass., assignor to
United-Carr Fastener Corporation, Cambridge,
Mass., a corporation of Massachusetts

Original application July 21, 1934, Serial No.
736,368. Divided and this application March
20, 1935, Serial No. 12,025

2 Claims. (Cl. 24—205)

My invention aims to provide improvements in sliders for use with multiple fasteners and in the method of making slider bodies.

This application is a division of my prior application Serial No. 736,368, filed July 21, 1934 and relating to my novel method of making my fastener sliders.

In the drawing, which illustrates a preferred embodiment of my invention:

10 Figure 1 is an elevational view of a portion of a multiple operable fastener installation showing my improved slider;

Fig. 2 is a side elevation of the slider;

Fig. 3 is a plan view of a portion of a strip 15 showing the method of forming the reinforcing rib;

Fig. 4 is a plan view of a portion of the strip showing the method of forming and blanking the slider body after the reinforcing rib has been formed;

Fig. 5 is a side view of the blank as it appears when cut from the strip;

Fig. 6 is a section of the slider taken on the line 6—6 of Fig. 1; and

25 Fig. 7 is an enlarged section of the slider taken on the line 7—7 of Fig. 2.

Referring now to the slider selected for illustration of my invention, I have shown one having a body formed from a single piece of sheet metal without the use of rivets or other pieces to stiffen and strengthen the body as has been necessary heretofore. The particular slider illustrated has a top plate portion 1 and a bottom plate portion 2 spaced a predetermined distance 30 from the top plate portion. Each plate portion has its side edges turned at substantially right angles to form flanges 3 facing each other and spaced slight distances apart to permit passage of the stringers 4 and 5, when the slider passes 35 over the fastener elements 6 shown in Fig. 1. The plate portions 1 and 2 are joined together at one end by a hollow rib 7 which is more or less U-shaped and extends at least part way along the outer faces of the plate portions 1 and 2. This rib has sides which are preferably flat and relatively close together, thereby stiffening the slider body so that the plate portions 1 and 2 are held in fixed planes as against any ordinary 45 stresses which may be exerted upon them in use. 50 That portion of the rib 7 located at the bottom of the slider, or in the bottom plate portion 2, is less pronounced than at the top side thereby overcoming any objectionable projection on the inner side of an installation to which the device 55 is to be applied. The rib portion at the top plate

1 may serve as a means to receive and hold the usual pull-tab, as shown in Figs. 1 and 2.

The plate portions are wider at the end where they are joined together by the rib than they are at their free ends (Fig. 7). This is for the purpose of providing for the necessary diverging channels. Cooperating with the flanges 3 to form these channels are a pair of projections 8 extending from the rib toward the other end of the slider body. I have tapered these projections so that when they are bent together they form a comparatively sharp edge which greatly aids the operation of the slider.

10 In Figs. 3 and 4, I have illustrated portions of a strip of sheet metal, such as is used in the manufacture of my invention, and clearly showing the successive steps in the forming of the slider. Beginning at A (Fig. 3) and proceeding through D, the steps consist of simple drawing operations which form the rib 7, in this illustration extending downwardly from the visible side. Step E is the final drawing operation upon the 15 rib and includes swaging a pair of depressions on opposite sides of the rib which later form the projections 8. These depressions become

20 regularly deeper toward their outer ends and are deepest at their ends. The next step F consists in piercing the holes 9, which mark the free ends of the plate portions 1 and 2 and leave a small connecting link 10 between the slider blanks so that they may be fed in a strip through 25 the press. In operation F I also pierce out the portions 11, thereby delineating the ends of the plates 1 and 2 which are adjacent to the neck portion when the slider is completed. It will

30 be noticed that one end of the rib is tapered to a comparatively thin point. This is the end that lies along the back plate. It also extends further toward the free end of the slider than the rib on the other plate. This is because it 35 is necessary to have a more pronounced projection on the front plate for the purpose of attaching the pull member. This piercing operation also cuts away the portions of the strip around the depressions leaving the projections 8, 40 which taper toward their free ends as described above. In step G, I commence the forming of the side flanges 3. This is a combined drawing and bending operation which results in making the flanges thinner than the plates when 45 finished. After the first flange-forming operation as at G, the sides of the plate portions 1 and 2 are freed by the blanking operation as at step H. During this operation the flanges 3 are completed. At step I, the portions 12 of the rib, be- 50

55

tween the projections 8 and the plate portions are swaged and curved toward each other until they meet and form tubular portions at each side of the projections. This is for the purpose 5 of making the rib more rigid and of presenting a neater and more compact finished slider. The final operation in this particular series is that of separating the partly finished slider from the strip as at 13 in step J.

10 Now there remains the bending of the rib to make the plates 1 and 2 lie in parallel planes. This is done so that the plates exactly overlie one another and their flanges extend directly toward each other with a space between them to permit 15 the passage of the fastener stringers. At this point the projections 8 are bent toward each other until they meet, their tapered ends forming a neat and smooth joint. The final step is that of sizing the slider to the very exact dimensions demanded 20 by the nature of the task it is to perform. The pull-tab may be attached to the rib on the front face of the slider by any suitable method. I prefer to drill holes in the rib to receive the connecting link of the tab (Figs. 1 and 2).

25 The slider I have described is simple, sturdy and neat in appearance. By virtue of its rib it will resist unusual strains in all directions. The method I have invented for making the slider is

novel and simple, easily and inexpensively performed.

While I have illustrated and described a form of my invention, I do not wish to be limited thereby, since the scope of my invention is best defined 5 by the following claims.

I claim:

1. A sheet metal slider for multiple fasteners having a body formed from a single piece of metal and having spaced top and bottom plates, a hollow stiffening rib providing the sole means joining said plates together in predetermined spaced relationship, the cross-sectional depth of the hollow of said rib at its greatest point being substantially greater than the thickness of the material of said 15 rib adjacent said hollow, and a pair of ears integral with said rib and extending into the space between said plates to form diverging channels.

2. A sheet metal slider for multiple fasteners having a body formed from a single piece of metal and having spaced top and bottom plates, a relatively deeply hollowed stiffening rib providing the sole means joining said plates together in predetermined spaced relationship, and integral projecting means extending directly inwardly from 20 the edges of said rib into the space between said plates to form diverging channels.

DIDRICK DYRESEN.
